SPINNING, DOUBLING, AND TWISTING
MACHINERY

Sebastian Ziani de Ferranti, deceased, late of Hollinwood, England, by Gertrude Ruth Ziani de Ferranti, executrix, Upper Basildon, Pangbourne, England, assignor to Ferranti Inc., New York, N. Y.

Original application February 8, 1934, Serial No. 710,366. Divided and this application December 31, 1934, Serial No. 760,001. In Great Britain February 13, 1933

7 Claims. (Cl. 118—51)

This application is divided out from application Serial No. 710,366 filed the 8th day of February, 1934.

This invention relates to spinning, doubling and twisting machinery, especially to machines of the high speed flyer type. Investigation of a comparatively large number of spindles of this type showed that much had still to be done to ensure the desired success both from the aspect of speeds and also from that of product, and especially from the aspect of obtaining the desired product at the desired speed.

Many Letters Patent were subsequently obtained by the late Dr. S. Z. de Ferranti dealing with improvements made from time to time, and the object of the present invention is to provide still further improvements.

The late Dr. Ferranti found that with the above object in view, the flyer should be balanced to a very high degree of accuracy, and special attention should be paid to spindle and flyer bearing constructions. The present application deals with improvements in such bearing structures and has for an object the provision of a device which is relatively cheap, simple in construction and capable of sustaining successfully speeds of rotation higher than those usually associated with such rotating machines.

A further object consists in providing improvements in the form, construction and arrangement of the several parts whereby the above and other objects may be effectively attained.

The invention is directed mainly to a construction of bearing in which an intermediate resiliently mounted tube carries the bearing surfaces from the rotary parts which are mounted thereon.

Other features of the invention will be made clear in the accompanying description.

An embodiment of this invention by way of example is represented in the accompanying drawings, in which:—

Figure 1 is a diagrammatic elevation of a spinning machine to which the present invention is applicable.

Figure 2 is a part sectional elevation of the spinning mechanism of Figure 1.

Figure 3 is a vertical section through the axis of a flyer bearing and driving mechanism with the flyer itself shown in position but not in section.

Figure 4 is a side elevation of the resilient mounting for the flyer bearing.

Figure 5 is a plan view of Figure 4.

Figure 6 is an underside plan view of Figure 4.

Figure 7 is a sectional elevation of a flyer.

Figure 8 is a section through the axis of the spindle and its associated mechanism with a bobbin tube shown in chain dotted lines.

Figure 9 is a detail of the top of the spindle running tube shown partly in section.

Figure 10 is a plan view of Figure 9.

Figure 11 is a detail view of the top of spindle bearing tube unit in section showing the valve seat for the running tube top bearing.

Figure 12 is a plan of the part shown in Figure 11.

Figure 13 is a detail view of the anti-vibration device for the top of the spindle carbon bearing tube.

Figure 14 is a plan of the part shown in Figure 13.

Figure 15 is a detail view of a damping device for the centre of the spindle carbon bearing tube.

Figure 16 is a developed view of the casing of the damping device shown in Figure 15.

Figure 17 is a detail of the anti-vibration device for the bottom of the spindle carbon bearing tube.

Figure 18 is a plan of the part shown in Figure 17.

Figure 19 is an elevation in part section of the bottom of the spindle running tube.

Referring to Figures 1 and 4, the bearings for the flyer 1 consist of a form of resilient or spring-supported bearing comprising two parts, namely, an outer cage 2 and an inner tube 3. The flyer 1 is air-borne along the axis of the inner tube 3 and within it, and this inner tube is spring-supported inside the cage 2. The inner tube consists of an electrodeposited copper shroud containing two carbon bearing surfaces 5 and 6. Near the top of this tube air from any convenient source enters the inlet 7 which communicates with a channel formed by two drillings 8 and 9 at right angles, for leading air to a space 7a beneath an air thrust washer 10 for keeping the rotating flyer assembly 1 from contact with the top of the flyer bearing tube 3 against the action of gravity. The bearing surfaces 5 and 6 within the tube are short in length and widely separated. The bearings are of moderate area, but need not be self-aligning; being divided they can distort through a comparatively great angle without upsetting conditions for the high speeds which come into question, especially where large bearing areas are to be avoided.

The outer cage 2 in which the flyer bearing tube 3, that is the inner tube, is suspended, consists of longitudinal strips of steel 11 with circumferential rings 12 welded to the strips.

- The flyer bearing tube 3 is held by two corrugated rings 13 and 14 in which it is a push fit with some means of preventing it rotating. These corrugated rings 13 and 14 are separated by 5 spring assemblies, 15 and 16 respectively, one at each end of the cage 2, each assembly consisting of three helical springs marked 17 and three marked 18, the mid points of the springs being attached to the flyer bearing tube supporting 10 rings 13 and their ends to the rings 12 by means of the brackets 19. Between the rings 13 and 14 and the surrounding cage 2 any known damping means such as felt strips may be inserted to 15 damp the resilient effect of the spring supports. The bearing and bearing cage referred to above provide a self-centering bearing for and support 20 the flyer; the corrugated rings 13 of the cage being adapted to engage grooves 21 on the outside of the flyer bearing tube 3.
- The position of the cage is located by a spring-pressed pin 24 which enters a hole in the surrounding casing.
- The spindle constructions and bearings and flyer constructions are preferably such as are 25 hereinafter described.
- The spindle assembly in one example shown in Figure 8 consists of three parts or components, namely an outer running tube 27 for carrying the bobbin 28, and having a brake drum 29 at the 30 base; an intermediate bearing tube 30, stationary but free to vibrate, having the same degrees of freedom as the running tube 27, except that of rotation about its axis, and having bearing surfaces 25 and 26 on which the running tube 27 rotates. The bearings 25 and 26 for the outer running tube of the spindle assembly made of carbon or the like are used to prevent seizing and may 35 be in two axially separate parts as shown in Figure 8 or may be a single long bearing.
- The bearing tube 30 is also provided with a thrust device, described below, forming a thrust, or carrying bearing for the running tube at the top. This intermediate tube 30 is spring-supported on a fixed inner dead spindle 31, which 40 incidentally is also provided with a braking assembly and a spring damping device as described below.
- The outer running tube 27 is formed of electro-deposited copper, a brass braking drum 29 being 45 secured to the base. The top of the tube 27 is closed by a cap 32 carrying a small valve spindle 33, the bottom part of which enters a valve seating in the top of the intermediate tube.
- The valve consists of a steel pin, the lower part 50 of which is of greater diameter than the remainder.
- The intermediate tube is formed of electro-deposited copper, and carries the bearing surfaces of carbon for the outer tube.
- The intermediate tube 30 is closed at the top by 55 a grooved graphite plug 34, held in place by a steel ring 35. It is bored centrally with a small hole 36 forming the seating for the valve pin 33 at the top of the outer running tube. The function of this valve is to enable air to pass by lifting the outer running tube to a certain extent, this lifting acting to cut off the air supply except for the leakage of air permitted by a small hole 37 in the outer running tube near the top. The 60 lower face of the graphite plug 34 is formed with a hemispherical seating 38 to take a brass swiveling air connecting piece 39, mounted in the top of the inner spindle 31.
- The inner spindle 31 consists of a steel tube 65 closed at the base by a plug 40 externally threaded

at 41 for mounting the tube in the rail 42. Alternatively, the spindle may be turned from the solid and internally drilled.

At the top of the spindle a resilient cage 43 for supporting the intermediate tube is mounted. The resilient cage consists of a lower brass ring 44 fixed to the spindle and an upper ring 45 with a substantial clearance about the spindle, the two rings being joined by a series of helical springs 46. Within the tube, in the vicinity of this cage, 10 there is provided a brass tubular connecting piece 39 with spherical ends, one bearing in the spindle and the other bearing the intermediate tube. Air passes through this connecting piece from the inside of the spindle to the inside of the intermediate tube. The dead spindle also carries a spring rod friction damper 47 for connecting with approximately the mid-point of the intermediate tube. The position, however, does not appear to be material.

This damping device, see Figures 15 and 16, consists of an outer cage 48 comprising top and bottom washers 49 and 50 respectively, having a substantial clearance with respect to the spindle 31, and loosely carrying a spring circlip or incomplete ring 51. Two further brass washers 52 and 53 are associated with the spindle; one 52, is located roughly in position between two shoulders 55 formed on the spindle by a split collar 58, a fibre or other damping washer 54 resting between the brass washer and the lower shoulder on the spindle. The top brass washer 53 of this part is also loose on the spindle, but has very little clearance. This point of clearance also applies to the bottom brass washer 52.

Between these two washers a light helical spring 56 is disposed. The clearances of these washers are less than the clearances of the washers of the outer assembly.

Between the two top brass washers 49 and 52 a 40 resilient washer 57 is provided. The resilient washers 54 and 57 act as friction washers, and are provided for that purpose.

The assembly apparently acts to prevent excessive amplitude of vibration which might be 45 caused by out-of-balance due to differences in winding of the cotton on the bobbin resulting from, for example, periodical uneven drag.

Having now described the invention what is claimed as new and desired to secure by Letters 50 Patent is:—

1. A bearing structure for the rotating parts of high speed machinery including a fixed support, an intermediate tubular support resilient means connecting said intermediate support to 55 said fixed support, a tubular rotating member, a bearing surface on said rotating member and a bearing surface on said intermediate member coacting with the bearing surface on said rotating member.

2. A bearing structure as claimed in claim 1 wherein said intermediate member is furnished with three bearing surfaces namely two longitudinally spaced circumferential bearing surfaces and a transverse end bearing surface on the top 65 of the intermediate member and the rotating member has corresponding coacting bearing surfaces.

3. A bearing structure for high rotational speeds comprising a fixed inner dead spindle provided with a resilient device and a damping device, an intermediate tube coaxial with said dead spindle and resiliently supported thereon by said resilient devices, a circumferential bearing surface near each end and a longitudinally bored 70 surface

plug having a lateral bearing surface at the upper end of said intermediate tube, an outer running tube also coaxial with said dead spindle, and bearing surfaces on the inner side of said running tube coacting with each of the said bearing surfaces on the intermediate tube.

4. A bearing structure as claimed in claim 3 including means for lubricating the bearing surfaces by air, said means comprising a longitudinal duct extending through the upper end of the dead spindle and a longitudinally bored member connecting the upper end of the longitudinal duct in the dead spindle with the lower end of the bore in the plug at the upper end of the intermediate tube.

5. A bearing structure as claimed in claim 3 including means for lubricating the bearing surfaces by air, said means comprising a longitudinal duct extending through the upper end of the dead spindle, a longitudinally bored member connecting the upper end of the longitudinal duct in the dead spindle with the lower end of the bore in the plug at the upper end of the intermediate tube, and a valve comprising a cylindrical closing member depending from the top bearing surface of the outer running tube coacting with a valve seat in and concentric with the bore in said plug.

6. A bearing structure as claimed in claim 3 including means for lubricating the bearing surfaces by air, said means comprising a longitudinal duct extending through the upper end of the dead spindle, a longitudinally bored member connecting the upper end of the longitudinal duct in

the dead spindle with the lower end of the bore in the plug at the upper end of the intermediate tube, and a valve comprising a cylindrical closing member depending from the top bearing surface of the outer running tube coacting with a valve seat in and concentric with the bore in said plug, the said resilient supporting device being in two parts located respectively near the ends of the dead spindle and the said damping device being located at an intermediate position on the dead spindle. 5

7. A bearing structure as claimed in claim 3 including means for lubricating the bearing surfaces by air, said means comprising a longitudinal duct extending through the upper end of the dead spindle, a longitudinally bored member connecting the upper end of the longitudinal duct in the dead spindle with the lower end of the bore in the plug at the upper end of the intermediate tube, and a valve comprising a cylindrical closing member depending from the top bearing surface of the outer running tube coacting with a valve seat in and concentric with the bore in said plug, the said resilient supporting device being in two parts located respectively near the ends of the dead spindle and the said damping device being located at an intermediate position on the dead spindle. 10 15 20 25
